[57] CLAIM

The ornamental design for an impact wrench, as shown and described.

DESCRIPTION

FIG. 1 is a front and top right perspective of an impact wrench, showing our new design;

FIG. 2 is a front elevational view of the impact wrench shown in FIG. 1;

FIG. 3 is a rear elevational view of the impact wrench shown in FIG. 1;

FIG. 4 is a right side elevational view of the impact wrench shown in FIG. 1;

FIG. 5 is a left side elevational view of the impact wrench shown in FIG. 1;

FIG. 6 is a top plan view of the impact wrench shown in FIG. 1;

FIG. 7 is a bottom plan view of the impact wrench shown in FIG. 1;

FIG. 8 is a front and top right perspective of an ergonomic switch shown in the environment of an impact wrench;

FIG. 9 is a front elevational view of the ergonomic switch shown in FIG. 8;

FIG. 10 is a right side elevational view of the ergonomic switch shown in FIG. 8;

FIG. 11 is a left side elevational view of the ergonomic switch shown in FIG. 8;

FIG. 12 is a top plan view of the ergonomic switch shown in FIG. 8, looking through the environment; and,

FIG. 13 is a bottom plan view of the ergonomic switch shown in FIG. 8.

The broken line showing of a impact wrench is for illustrative purposes only and forms no part of the claimed design.
